UNITED STATES PATENT OFFICE.

BIRNEY DYSART, OF ST. LOUIS, MISSOURI, ASSIGNOR TO ADDING TYPEWRITER COMPANY,
OF ST. LOUIS, MISSOURI, A CORPORATION OF MISSOURI.

RECORDING-MACHINE.

No. 913,880.

Specification of Letters Patent. Patented March 2, 1909.

Application filed May 14, 1906, Serial No. 316,639. Renewed July 13, 1908. Serial No. 444,202.

To all whom it may concern:

Be it known that I, BIRNEY DYSART, a citizen of the United States, residing at St. Louis, Missouri, have invented a new and useful Recording-Machine, of which the following is a specification.

This invention relates to recording machines, and more particularly to mechanism for moving the paper to different positions to receive different columns of records, and it consists of the novel construction, combination and arrangement of parts hereinafter shown, described and claimed.

The present invention has for its object to provide mechanism adapted for use in connection with recording machines wherein it is desirable to shift the paper laterally as required to receive records in different columns or in different lateral spaces, and includes in its construction mechanism for moving the paper in line spacing. The mechanism for subserving these functions includes a paper carriage or platen for holding the paper, mechanism associated and connected with the paper carriage or platen for moving the paper as required for line spacing, and mechanism whereby the paper can be moved to different positions to present different column spaces for receiving records, without causing the platen to travel. Such, broadly, is the object of, and the mechanism comprising, the invention. For convenience, as one form of its practical reduction, the invention is shown in connection with an adding and recording machine of the kind invented by Hubert Hopkins, and as disclosed in his application for patent filed July 14, 1902, Serial No. 115,411, refiled July 31, 1905, Serial No. 271,986, for an adding machine, and in his application for patent filed January 24, 1903, Serial No. 140,390, for an adding and writing machine, but it can be applied to, or built in connection with, any machine wherein it is possible to record upon paper broad enough to receive more than one column of records.

Referring to the accompanying drawings which form part of this specification, Figure 1 shows a paper carriage or platen constructed in accordance with and embodying my invention. Fig. 2 is a cross sectional view taken approximately on the line 2—2 of Fig. 1. Fig. 3 is a cross sectional view taken on the line 3—3 of Fig. 1. Fig. 4 is a similar

sectional view substantially on the line 55 4—4 in Fig. 1. Fig. 5 is a perspective view of a pair of suspended bearings forming part of the column spacing mechanism. Fig. 6 is a view of a portion of the space-controlling mechanism. Figs. 7 and 8 are views of a 60 part of the spacing frame mechanism. Fig. 9 is a side elevation of a recording machine showing the invention in connection therewith.

By some meritorious recording machines 65 now being manufactured it is impossible to produce more than one column of records because such machines do not contain any mechanism for moving the paper to present different columns. This is especially true of 70 some of the adding and recording machines, and some of the register-recording machines. Moreover, in some of those machines it is impossible to apply or construct any of those tabulating devices which require or involve 75 lateral travel of the platen in order to present different columns on the paper to receive records. For such machines, and for any machine wherein it is not desirable to employ the laterally traveling paper carriage or 80 platen, this invention is obviously applicable.

In its present construction the invention is shown in combination with and as a part of a recording machine, the case of which is 85 indicated by 5, the entire paper carrying mechanism being shown in position to receive records which will be visible to the operator as they are made. In this type of machines the matter to be recorded is first 90 introduced into the machine by being struck on the keys 6. The operating handle 7 is then drawn forward, and such operation results in movement of the type-carriers 8 toward recording position, said type-carriers 95 being stopped automatically to present at the recording point that matter which had been struck on the keys. There are several of these type-carriers and they operate side by side to present the necessary number of 100 type—whether one or several—side by side at the printing or recording point. The types are indicated by 9. After the types have been alined for printing they are driven to print by means of hammers 10 which are 105 automatically thrown against the types at the proper time, all as fully illustrated and described in the applications of Hubert Hop-

kins above referred to. A lever 11 pivoted at 12 is swung forward a short distance by automatic means as the handle 7 moves, this part operating as described in application 5 Serial No. 140,390 filed Jan. 24, 1903 by Hubert Hopkins as aforesaid.

So far the machine is complete as constructed. My invention comprising the novel paper carriage or platen in combination therewith and as applied thereon is supported by the frame pieces 13, being a part of or attached to the machine frame. The platen shaft 14 is journaled in said frame pieces and carries a roller 15 divided, 15 as shown in Fig. 1, into a number of separate sections, one of which is always in position for receiving the blow of the type 9 in printing. This platen is not movable laterally, and, in order to place different columns of 20 the paper in position to receive records, it is necessary to move the paper. I will now describe the mechanism for moving the paper for such purposes.

Two rods 16 are fastened between the frame pieces 13, and each of such rods carries a number of brackets 17; a frame 18, comprising a front part and a rear part which are parallel and the ends of which are connected, is mounted to slide laterally in said 30 brackets. A rack 19 is carried by the front part of said frame and a like rack, similarly indicated, is carried by the rear part of the frame. On the rods 16, between the sections of the platen, are carried coöperating 35 parts 20 (Fig. 5) each comprising a horizontal and a vertical arm, and the vertical arm on each part having lateral extensions 20^a. In the lateral extensions on each part 20 a trunnion 21 is journaled, on the upper 40 ends whereof pinions 22 are attached, said pinions meshing with the racks 19, resulting in rotation of the trunnions 21 when the racks are moved. A roller 23, is fastened on the lower end of each trunnion 21. As 45 usual, a paper guide plate 24 is utilized to direct the paper around the platen. A number of rollers 25 are supported in the rear of the platen, in this instance on extended portions of the guide plate, said rollers being 50 in line with the rollers 23 and extending to the plane of the platen, (see Fig. 4) so that the paper can pass between them and the platen without obstruction. Similarly, a number of rollers 26 are supported in front 55 of the platen on extended portions of the paper guide plate. These rollers 25 and 26, coöperating with the rollers 23, engage the paper and move it laterally at the proper time, being controlled and actuated in the 60 performance of their functions by suitable mechanisms to be described.

The vertical arms of the parts 20 are connected by springs 27, which draw the rollers 23 away from the rollers 25 and 26 to permit 65 passage of the paper. The horizontal arms

of the parts 20 are connected by pin-and-slot connection 28, so that upward or downward movement of either of such arms will cause like movement of the other. The arm on one of the parts in each pair has a tooth 28^a. 70 A rod or bar 29 is carried by the frame 18 crosswise just over the horizontal arms of the parts 20. Knobs 30 are attached to the ends of said bar for manual rotation thereof. One side of the bar 29 is a plane as shown at 31 75 and when this side is turned downward it permits the ends of the horizontal arms of the parts 20 to rise so that the rollers 23 will be drawn away from the rollers 25 and 26, and permit movement of the paper for line spacing in any location that the said bar may be. Other sides of the bar have notches 32 at different distances apart and when either of the notched sides of the bar is downward, the horizontal arms of the parts 20 will be held 80 down, thereby holding the rollers 23 against the rollers 25 and 26, except when the bar is in such position that the teeth 28^a on the parts 20 can enter the notches 32, during which latter period the springs 27 draw the 90 rollers 23 away from the said rollers 25 and 26, and leave the paper free for its line spacing movement. One end of the bar 29 is squared as shown at 33, (Figs. 6 and 8) and a spring 34 attached to the frame 18, by bearing against the squared part of the bar holds 95 said bar in its different adjustments.

The paper is moved laterally for column spacing by forcing the rollers 23 outward to engage the paper and then rotating the rollers by moving the frame 18 the required distance in the direction of desired movement. A bar 35 extends across the horizontal arms of the parts 20, and a lever 36 is connected to said bar, the lever being pivoted at 37 to the frame 18. From the foregoing it is clear that, by pushing down the lever 36, the arms of the parts 20 will be disengaged from the notches in the bar 29, and at the same time the paper will be engaged between the rollers 23, and 25, 26. Then by moving the frame 18, which may be done by retaining hold of the lever 36, the paper will be moved in the same direction and the same distance. When either of the notched sides of the bar 110 35 is downward, if the operator, after moving the paper a short distance, will refrain from further depression of the lever 36, the paper will be automatically stopped, when it has moved a column space, by the teeth 28^a 115 again entering notches 32.

38 indicates a feed roller operating, in connection with the platen, to assist in inserting and moving the paper in line spacing. This roller is supported by two levers 39 pivoted 120 to the frame pieces 13, and actuated by springs 40 (Fig. 3) to hold the roller against the platen. Oscillation of the levers 39 in opposition to their springs 40 will move the roller 38 away from the platen and thereby 130

leave the paper loose for lateral movement. For this purpose a rock shaft 41 has arms 42 extending under the projecting pins of the connection 28, and levers 43 bearing against 5 inclined surfaces of the levers 39, so that, through the various parts described, operation of the lever 36 will instantly move the roller 38 away from the platen, and thereby leave the paper loose for lateral movement. 10 The levers 43 are provided with extensions on their free ends for manual engagement so that the paper can be released from the feed roller without operation of the lever 36.

Upon each end of the platen shaft a knob 15 44 is fastened for manual rotation of the platen. Rotation thereof for line spacing is automatically accomplished, the platen being turned the required distance upon each operation of the handle 7. As fully described 20 in the application Serial No. 140,390 for an adding and writing machine, filed January 24, 1903 by Hubert Hopkins, a lever corresponding to lever 11 is oscillated each time 25 the handle 7 is operated. In the present embodiment of my invention that lever is utilized. The upper end thereof has a slot 45 (Fig. 4). A rod 46 is supported by two links 47 swinging from the platen shaft, and said links 47 are connected to levers 48 by connecting links 49. A pawl 50 is pivoted to the upper end of each of the levers 49, said pawls riding upon ratchet wheels 51, so that the oscillation of the lever 11 results in operation of the levers 49, and consequently in 35 rotation of the platen by said pawls. Since the lever 11 is oscillated each time a separate part of the record is produced, it follows that the paper is automatically moved the required distance to cause the various separate 40 parts of the record in each column to be recorded on different lines.

It will be apparent to those skilled in the art to which this invention pertains that this paper moving mechanism can be applied to 45 machines of various other constructions than those specifically referred to. Therefore I do not restrict myself to those specific constructions except in the claims reciting those constructions. Variations from the 50 construction described may be made within equivalent limits without departing from the spirit and scope of my invention.

Having described my invention what I claim is:

55 1. The combination with a paper holder and mechanism for recording on paper thereon, of mechanism for moving the paper laterally relative to the holder.

2. The combination with a platen arranged 60 to carry paper, and mechanism for recording thereon, of mechanism for moving the paper for line spacing, and mechanism for moving the paper laterally relative to the platen.

3. The combination with a platen arranged 65 to carry paper, and mechanism for recording

on the paper, of mechanism operable automatically by the recording mechanism to move the paper for line spacing, and mechanism operable to move the paper laterally relative to the platen. 70

4. The combination with a platen arranged to carry paper, and mechanism operable to record two or more characters side by side on the paper without moving the platen, of mechanism operable to move the paper laterally relative to the platen. 75

5. The combination with a platen arranged to carry paper, and separately movable devices operable to record two or more characters side by side on the platen without moving the platen, of mechanism operable to move the paper laterally relative to the platen. 80

6. The combination with a platen arranged to carry paper, and mechanism operable to record two or more characters side by side on the platen, of mechanism operable to move the paper for line spacing, and mechanism operable to move the paper laterally relative to the platen. 85

7. The combination with a platen arranged to carry paper, and separately movable devices operable to record two or more characters side by side on the platen without moving the platen, of mechanism operable to move the paper for line spacing; and mechanism operable to move the paper laterally relative to the platen. 90

8. The combination with a platen arranged to carry paper, and mechanism for recording on the paper, of mechanism operable automatically to move the paper for line spacing, and mechanism operable to move the paper laterally relative to the platen. 100

9. The combination with a platen arranged to carry paper, mechanism operable to record on the paper, and line spacing mechanism, of means for releasing the paper from the line spacing mechanism, and mechanism operable to move the paper laterally relative to the platen. 105

10. The combination with movable type-carrying parts, and devices for driving the type as required to make impressions on paper, of a platen arranged to carry paper, and mechanism operable to move the paper laterally relative to the platen. 115

11. The combination with type-carrying parts movable side by side, type on said parts and devices for driving the type as required to make impressions, of a platen arranged to carry paper, mechanism operable to rotate the platen for line spacing, and mechanism operable to move the paper laterally relative to the platen. 120

12. The combination with the platen of a recording machine, of mechanism operable to move paper laterally relative to the platen. 125

13. In a recording machine, a platen arranged to carry paper, mechanism for holding the paper on the platen, means for re- 130

- leasing the holding mechanism, and mechanism for moving the paper laterally relative to the platen.
14. In a recording machine, a platen arranged to carry paper, automatic mechanism for rotating the platen, a lever, and mechanism controlled by said lever for moving the paper laterally relative to the platen.
15. In a recording machine, a platen arranged to carry paper, mechanism operable to engage the paper, and means to cause said mechanism to move the paper laterally relative to the platen.
16. In a recording machine, a platen arranged to carry paper, mechanism for moving the paper laterally relative to the platen, and automatic means to stop the paper after it has moved laterally the width of a column space.
17. In a recording machine a platen arranged to carry paper, means to hold the paper on the platen, means for releasing said holding means, mechanism for moving the paper laterally relative to the platen, and automatic means to stop the paper after it has moved the width of a column space.
18. The combination with two or more movable type-carrying parts operable side by side to perform recording functions, and devices for driving the type as required to make impressions on paper, of a platen arranged to carry paper, and mechanism operable to adjust the paper and type-carrying parts relative to each other while the platen is stationary, as required to produce records in different vertical columns, substantially as specified.
19. The combination with type-carrying parts movable side by side to perform recording functions, type on said parts, and means for producing records on paper by use of said type, of a support arranged to hold paper, and means for causing the type to record in different vertical columns on the paper while the support is stationary, substantially as specified.
20. The combination with a platen arranged to hold paper, and mechanism for recording on paper held by the platen, of means operable to move the paper laterally relative to the platen while the recording mechanism is idle, substantially as specified.
21. The combination with a platen arranged to hold paper, and mechanism for recording on paper held by the platen, of means operable to move the paper laterally relative to the recording mechanism while the platen is stationary, substantially as specified.
22. The combination with a platen arranged to hold paper, and mechanism for recording on paper held by the platen, of manually operable means to move the paper laterally relative to the recording mechanism while the platen is stationary, substantially as specified.
23. The combination with recording mechanism, and a platen arranged to hold paper, of mechanism operable to move the paper laterally relative to the platen, and column space stops, whereby the paper will be stopped at predetermined column spaces, substantially as specified.
24. A platen, recording instrumentalities to record on paper held by the platen, and mechanism operable to position different vertical columns of the paper to receive records while the platen is stationary, substantially as specified.
25. The combination with recording instrumentalities, and a laterally immovable platen arranged to support paper to be recorded on by said instrumentalities, of mechanism operable to adjust the paper and recording instrumentalities in such relation that different vertical columns of records may be produced, substantially as specified.
26. The combination with a laterally immovable platen arranged to hold paper, and recording instrumentalities operable to record on paper held by said platen, of devices operable to engage the paper and to move it laterally for column spacing, substantially as specified.
27. A platen arranged to hold paper, devices operable to engage the paper and to move it laterally relative to the platen for column spacing or other purposes, and mechanism operable to record one or more characters in each line within each column space, substantially as specified.
28. A platen arranged to hold paper, mechanism for recording on the paper held by the platen, clamp devices operable to engage with the paper, means for operating the clamp devices to move the paper for column spacing, and means to release said clamp devices from the paper, substantially as specified.
29. A platen arranged to carry paper, means to feed paper against the platen, means to record on the paper, and means operable to move the paper laterally to different positions relative to the platen, substantially as specified.
30. A platen, means to feed paper against the platen both laterally and longitudinally, and means to record on the paper in its different positions, substantially as specified.
31. A platen, recording devices operable to record on paper held by said platen, mechanism operable to position different vertical columns of the paper to receive records while the platen is stationary, and column space stops whereby the paper will be stopped at predetermined column spaces, substantially as specified.
32. A platen, means to feed the paper for

- line spacing, means operable to move the paper laterally to different positions relative to the platen, and column space stops whereby the paper will be stopped at predetermined column spaces, substantially as specified.
33. A platen, means to hold the paper against the platen, means to move the paper laterally relative to the platen, and column space stops whereby the paper will be stopped at predetermined column spaces, substantially as specified.
34. The combination with a revolute platen arranged to hold paper, of mechanism operable to move the paper laterally relative to the platen, substantially as specified.
35. The combination with a revolute
- platen arranged to hold paper, of manually operable means for moving the paper laterally relative to the platen, substantially as specified.
36. The combination with a revolute platen arranged to hold paper, mechanism for recording on paper held by said platen, and automatic means for moving the paper in line spacing, of means operable to move the paper laterally relative to the platen, substantially as specified.

In witness whereof I hereto affix my signature in the presence of two witnesses.
